PAIR OF GOGGLES

Francis J. Corrigan, Kutztown, Pa.

Application November 25, 1952, Serial No. 22,441

Term of patent 14 years

(Cl. D57—1)

To all whom it may concern:

Be it known that I, Francis J. Corrigan, a citizen of the United States of America, residing in Kutztown, county of Berks, State of Pennsylvania, have invented a new, original, and ornamental Design for a Pair of Goggles, of which the following is a specification, reference being had to the accompanying drawing, forming part thereof, wherein:

I claim:

The ornamental design for a pair of goggles, substantially as shown.

FRANCIS J. CORRIGAN.
